Primary Examiner — Cathron Brooks*Assistant Examiner* — Cary M Robinson(74) *Attorney, Agent, or Firm* — Cantor Colburn LLP(57) **CLAIM**

We claim, the ornamental design for a display screen or portion thereof with icon, as shown and described.

DESCRIPTION

The single FIGURE is a front view of a display screen or portion thereof with icon showing our new design.

The broken lines around the FIGURE illustrates a display screen or portion thereof and form no part of the claimed design.
